UNITED STATES PATENT OFFICE.

ALBERT W. QUATTLEBAUM AND BEN S. MOONEY, OF STATESBORO, GEORGIA.

APPARATUS FOR DISTILLING WOOD.

1,215,990.

Specification of Letters Patent. Patented Feb. 13, 1917.

Application filed June 3, 1913. Serial No. 771,548.

To all whom it may concern:

Be it known that we, ALBERT W. QUATTLEBAUM and BEN S. MOONEY, citizens of the United States, residing at Statesboro, in the county of Bulloch, State of Georgia, have invented certain new and useful Improvements in Apparatus for Distilling Wood; and we do hereby declare the following to be a full, clear, and exact description 10 of the invention, such as will enable others skilled in the art to which it appertains to make and use the same.

The present invention is directed to an apparatus for distilling wood, and has for its 15 object to so construct a device of this character that the wood is acted upon in the distillation process at the bottom of the retort or still.

With this and other objects in view, this 20 invention resides in the novel features of construction, formation, combination and arrangement of parts to be hereinafter more fully described, claimed and illustrated in the accompanying drawing, in which:—

25 Figure 1 is a side elevation of the apparatus.

Fig. 2 is a vertical sectional view through the same.

30 Fig. 3 is a sectional view on line 3—3 of Fig. 2.

Fig. 4 is a top plan view of the apparatus.

Referring to the drawing, the numeral 1 designates the furnace, which is formed from brick and is conical in shape, the same 35 being provided with a fire box 2, which surrounds the sheet metal still or retort 3, the upper end of which is open and projects above the furnace 1. The projected end of the retort 3 is provided with an annular 40 groove 4 which receives the depending flange 5 of the cover 6, said cover being held in place by a bar 7, which is arranged transversely thereof and has its opposite ends engaged in ears 8.

45 As will be seen by reference to Figs. 2 and 3, the bottom of the retort 3 rests upon a cylindrical supporting wall 19, forming part of the furnace structure, while 20 designates a second wall of substantially the same 50 height as the wall 19, this second wall lying

alongside the inner face of the furnace 1, and therefore, is spaced apart from the wall 19. The grate of the furnace which is indicated at 21 rests upon these walls 19 and 20 and surrounds the bottom end of the retort 3, as clearly shown in Fig. 3.

The lower end of the retort 3 is formed with a tapered portion 9 above which is supported a grate 10, upon which is mounted a screen 11, which prevents particles of coal or the like from entering the tapered portion 9, but allowing the free passage of gases or substance from the wood which is placed in the retort 3 and rests upon the screen 11.

Leading from the tapered portion 9 is a 65 pipe 12, which connects with the worm 13, said worm being arranged in a tank 14 containing cold water.

A pipe 15 leads from the worm 13 to a receiver 16, which is connected by a pipe 17 70 to a second receiver 18, into which the substance flows after being condensed as it passes through the worm 13.

From this construction it will be seen that upon starting the fire in the fire box 2, the 75 heat therefrom will act upon the wood contained in the retort 3 to extract downwardly the substance from the wood which gravitates to the portion 9 and thence to the worm 13, and during the passage therethrough it is 80 condensed and discharged into the receivers 16 and 18 in the form of turpentine.

What is claimed is:—

In a wood distilling apparatus, the combination with a furnace having a cylindrical 85 lower wall portion, and a fuel feeding opening and an opening in its top for the escape of products of combustion, a cylindrical supporting wall, within the furnace and spaced from the lower cylindrical wall, a retort 90 including a container seated upon the supporting wall, a grate supported upon the supporting wall and the wall of the furnace, said grate entirely surrounding the container and engaging the lower end thereof, the upper portion of the furnace wall being beehive in shape and provided with an opening 95 in its top disposed between the fuel feeding opening and the opening for the escape of products of combustion and through which 100

the container extends, the side wall of said container engaging the wall of said opening, a circumscribing flange on the upper end of the container disposed outwardly of the furnace and engaging the wall thereof, a removable cover for the container, and a conducting pipe leading from the bottom of the container to the outside of the furnace.

In testimony whereof we affix our signatures in the presence of two witnesses.

ALBERT W. QUATTLEBAUM.
BEN S. MOONEY.
